UPPER BOWL FOR A COFFEE BREWER

Edward C. Neuman, Oak Park, Ill., assignor to Cory Corporation, Chicago, Ill., a corporation of Delaware

Application January 23, 1951, Serial No. 13,915

Term of patent 14 years

(Cl. D44—26)

To all whom it may concern:

Be it known that I, Edward C. Neuman, a citizen of the United States, residing at Oak Park, in the county of Cook and State of Illinois, have invented a new, original, and ornamental Design for an Upper Bowl for a Coffee Brewer, of which the following is a specification, reference being had to the accompanying drawing, forming part thereof, wherein:

Fig. 2 is a side elevational view thereof, partly broken away in order to show a portion of the bowl wall in section, and the stem being shown broken away for convenience of illustration.

I claim:

The ornamental design for an upper bowl for a coffee brewer, as shown and described.

EDWARD C. NEUMAN.
